UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPEWRITING MACHINE.

1,413,648.

Specification of Letters Patent. Patented Apr. 25, 1922.

Application filed September 5, 1919. Serial No. 321,864.

To all whom it may concern:

Be it known that I, CLIO B. YAW, citizen of the United States, and resident of Arlington, in the county of Hudson and State of New Jersey, have invented certain new and useful Improvements in Typewriting Machines, of which the following is a specification.

The general object of my present invention is to provide a novel typewriting machine provided with new and improved mechanism for feeding and controlling paper, and more especially fan-fold sheets and the carbon sheets interleaved with the fan-fold sheets, although of course it is to be understood that the invention is not restricted to any particular character of work sheet or paper. More specific objects are the provision of a new and improved main paper carriage and its mounting; improved paper clamping, and smoothing or ironing devices; improved carbon carrying and feeding devices; improved carriage feed devices; and improved platen or type backing devices. Other objects will hereinafter appear.

To the above ends, my invention consists in the features of construction, combinations of devices, and arrangements of parts hereinafter described and particularly pointed out in the claims.

With the primary purpose of designing a mechanism which would be especially adapted for what is known as fan fold billing work, I have provided a typewriting machine comprising a main frame in which are mounted rearwardly striking type bars and their actuating mechanisms, as well as letter feeding or escapement devices, ribbon mechanism, tabulating mechanism and other parts usually found in typewriting machines, and I have combined therewith an upright or vertically disposed carriage structure arranged behind the main frame and adapted to travel or reciprocate for letter feeding on ways arranged at the rear of the main frame. This carriage structure carries a flat or bar platen and is provided with secondary or subordinate carriages, carriers or controllers adapted to slide or reciprocate vertically. One of these secondary carriages is provided with a clamp which holds the upper end of the fan-fold sheet, the lower portion thereof passing between spring pressed jaws or bars which are effective to iron out the usual creases extend-

ing transversely of the long fan-fold strip, these two paper controlling or holding devices co-operating to maintain the fan-fold strip in a taut flat condition vertically disposed behind the main frame and on the vertical carriage. The clamp carrier or controller is fed or advanced upward progressively step-by-step to line feed the fan-fold sheet across the bar platen which extends transversely behind it, the line feeding or spacing handle serving also to return the main carriage and all the parts carried by it from left to right to begin a new line. A second additional carriage on the main carriage is a vertically slidable paper controller or carbon carrier, which is provided with sets of pins adapted to receive detachable carbon holders carrying strips or short sheets of carbon paper that are adapted to be inserted between the leaves of the fan-fold sheet from opposite sides. Novel devices are provided for giving the carbon carrier, and through it the carbon strips, a slight automatic feeding movement at each reciprocation of the main carriage, this feeding movement which may be designated as a "creeping carbon feed" being so slight that a comparatively short strip of carbon may be employed for writing an ordinary half day's work on one face of an extremely long fan-fold web or strip, completely exhausting the carbon before it need be discarded. The principles of my invention make it highly useful in connection with various kinds of what is known as collating work, as I have in effect adapted a flat platen construction to a front strike typewriting machine, and hence I do not wish to be limited always to the use of mechanism with fan fold sheets.

The invention will be described in detail in connection with the accompanying drawings wherein,

Figure 1 is a side elevation of a typewriting machine embodying my invention, parts being omitted and other parts being broken away.

Figure 1^a is a perspective view, on a reduced scale, of a special table or support for the typewriting machine.

Figure 2 is a rear elevation of the traveling carriage of the machine, parts of the main frame and the stationary guide rails of the carriage also being shown.

Figures 3, 4 and 5 are sectional views taken on planes indicated in Figure 2 by the

respective dotted lines *s s*, *t t*, and *u u*, appearing as when viewed from the front of the machine and looking downward, the views being on an enlarged scale and the 5 main frame shown in Figure 2 being omitted.

Figure 5^a is a transverse sectional view taken on a plane indicated by the dotted line *u' u'* in Figure 5, and looking in the 10 direction of the arrow at said line.

Figure 6 is a vertical sectional view on an enlarged scale, the section being taken on a plane indicated by the dotted line *v v* in Figure 2 and looking in the direction of 15 the arrow at said line.

Figure 7 is a vertical sectional view taken on planes indicated by the broken dotted line *w w* in Figure 6 and looking in the direction of the arrow at said line.

20 Figure 8 is a sectional view taken on the dotted line *x x* in Figure 6 and looking in the direction of the arrow at said line.

Figure 9 is a fragmentary perspective view of the main carriage with the subordinate carriages removed.

Figure 10 is a perspective view of the carbon carrier or controller with one of the carbon holders in place thereon.

Figure 11 is a fragmentary perspective 30 view, on a larger scale, of the subordinate paper carriage or slidable clamping frame.

Figure 12 is a fragmentary end view, partly in section, showing details of the carbon feed mechanism.

35 Figure 13 is a vertical sectional view taken on a plane indicated by the dotted line *y—y* in Figure 12 and looking in the direction of the arrow.

Figure 14 is a vertical fore and aft sectional view of the machine omitting various 40 parts but showing the carriage feeding or escapement devices, together with certain of the devices for releasing the carriage by the release key and by the tabulator key.

45 Figure 15 is a detail view of the swinging support of the escapement wheel and pinion and associate parts.

Figure 16 is a plan view of the escapement rocker or dog carrier.

50 As appears from Figs. 1 and 2 the main frame of the machine comprises a rectangular base portion 1, open at the rear, side plates 2 suitably secured to the base as by screws 3 and co-operating nuts 4, and a top plate 5 superposed on and fixed to the side plates. A detachable front plate 6 may also be provided for covering the type bar mechanism and other parts. The main frame contains and supports the type bar system, the 55 ribbon mechanism, the carriage feeding or escapement mechanism, parts of the tabulating mechanism and other appurtenances common to typewriting machines. The type bars are of the front strike variety, the individual type bars indicated at 7 which con-

stitute the system being arranged in an arc of a circle and pivoted on a pivot wire 8 which in turn is supported on an inclined type bar segment or stationary support 9, said segment being secured to projections or 70 lugs 10 which are fixed as by screws 11 to the side plates 2 and project inward therefrom towards each other. The type bars 7 are arranged in guide slots 9^a formed in the segment 9 and are normally supported near 75 their free ends by an arcuate type rest 12 which at its ends has depending arms 13 that are secured to the top plate 5. Each type bar is actuated by a train of devices co-operating with a slot or cam-way 14 formed in 80 its heel portion, said train comprising a pin 15 engaging in said cam-way and projecting laterally from the upwardly extending arm 16 of a bell crank lever which comprises also a short arm 17. Said bell crank is pivoted 85 on a pivot wire 18 common to all of the bell cranks and supported on a stationary support 19 provided with slots 20 in which the bell cranks are received. Links 21 connect the short arms 17 of the bell cranks with 90 key levers 22, the system of key levers being pivoted in rear of the base on a common pivotal support 23, and each being provided at its front end with a key button or cap 24; these caps being arranged as usual on stem 95 portions 22^a that project upward at an angle from the body portions of the key levers, thus providing a keyboard as the front of the main frame. While case shifting mechanism may be employed if desired, the character of work for which my present invention is more particularly designed, does not require two types on a bar, a single type as shown being all that it is necessary to provide for each type bar, and hence case 100 shifting mechanism is not needed. On depressing the key levers their associate type bars are swung upward and rearward by the described trains of mechanism so that the types co-operate with the front face of a 110 platen hereinafter described.

The types are adapted to print through the printing portion of a ribbon 25 that is wound upon spools 26, these spools being contained in stationary cups or housings 27 115 arranged above the top plate at opposite sides of the machine. The spools are adapted to be turned in alternation to feed the ribbon back and forth by any suitable mechanism. Such ribbon feeding mechanism is 120 not disclosed in the drawing but I have employed in my machine the ribbon feeding mechanism of the No. 10 Remington machine, and prefer to employ ribbon feeding mechanism of this general character. The 125 printing portion of the ribbon is threaded through and controlled by a vibratory ribbon carrier 28, Fig. 14, which at its upper end is guided in stationary grooved ways 29 fixed behind the center guide 30 of the 130

type bars. The ribbon vibrator is actuated at each stroke of a printing key by a train of devices comprising a lever 31 to which the lower end of the vibrator is pivotally connected, said lever being horizontally disposed and its pivot 32 having a stationary bearing. The forward arm of said lever 31 is pivotally connected to the upper end of a link 33, which extends downward and has 10 its lower end pivoted to the universal bar of the machine underlying the key levers.

Mounted in the rear portion of the base is the carriage feeding or escapement mechanism which co-operates with a rack 35 on 15 the carriage of the machine, as hereinafter more fully described. Referring especially to Figs. 1, 4, 14, 15 and 16, the carriage rack 35 has forwardly extending teeth which mesh with the teeth of a gear wheel 36 20 which is rigid on an axle to which one end of a main or propelling spring 37 is secured, the said axle being mounted in a stationary bracket 37^a (Fig. 2) in the rear of the machine frame. This main spring mechanism 25 may be of any desired construction, such for example as that found in the Smith Premier machine. It will be understood that the tendency of the main spring 37 is constantly to urge the rack 35 and the part to which 30 it is secured leftward across the machine. To the right of the gear wheel 36 and also meshing with the rack 35 is a feed pinion 38 secured to the upper end portion of a vertically disposed shaft 39, said shaft near 35 its lower end having secured to it a toothed escapement wheel 40. The shaft bears in an open frame 41 which near its middle has a rightward extension 41^a that is formed with a hole in line with a corresponding hole 40 in the frame 41 to bear on adjustable screw pivots 42 that project outward from a support or block 43 fixed by screws 43^a to an angle bar 43^b screwed fast to the under side of the lower one of a pair of stationary guide 45 rails 44. Said rails have more especially to do with the carriage to be described in detail hereinafter. A set of leaf springs 45 secured by screws 46 to the support 43 co-operate with the frame 41 to maintain it 50 normally in the position shown in Fig. 14. Adapted to co-operate with the escapement wheel 40 are escapement dogs 47 and 48 mounted on a dog rocker 49. The stepping or feed dog 47, which is normally engaged 55 with the escapement wheel, is arranged on the top of the dog rocker 49 and comprises two parts, the dog proper 47 and a supporting part 47^a to which the part 47 is pivoted, the part 47^a in turn having a pivot 60 50 on the dog rocker, and the two-part dog being normally maintained against a stop pin 51 by a coiled spring 52. A second coiled spring 53 connects the two parts 47 and 47^a and permits the part 47 to yield in a backward direction during return movements of 65 the carriage. A stop pin 51^a at the left of the stepping dog limits the extent of its stepping movement. The dog rocker 49 is fixed to the middle portion of a rock shaft 54 which bears at its ends on screw pivots 70 secured to the sides of the base. A set screw 55 maintains a fixed relationship between the dog rocker and the rock shaft 54. Fixed to the rock shaft 54 near its ends are inclined arms 56 which are connected beneath the key levers by a universal bar or rod 57, which the key levers depress during printing operations, causing a vibration of the dog rocker and a co-action of the dogs and escapement wheel, as is usual, to permit 75 step-by-step feeding movements of the carriage, and also actuating the connected link 33 of the ribbon vibrating mechanism.

Tabulating devices (Figs. 1, 5 and 14), are mounted on the main frame, said devices 80 comprising a lever arm 58 fixed to the right-hand end portion of a rock shaft 59 that extends transversely of the base and bears at its ends on fixed pivotal bearings. The lever arm 58 extends upward and forward and is 85 provided with a vertical key stem 60 that is capped by a tabulator key 61 disposed at the right of the keyboard. A coiled restoring spring 62 is connected to the arm 58 and to a stationary anchorage 63. Fixed to the 90 middle portion of the rock shaft 59 is a two-ply arm or stop member 64 that extends rearward, said arm constituting a frame stop that co-operates with the movable tabulator 95 stops on the carriage, as hereinafter described. Also fixed to the rock shaft at the right of the two-ply arm 64 is an upwardly extending arm 65 that is pivotally connected at 66 to an arm or rod 67 that extends rearward, passing through a thin plate-like extension or finger 68 secured to the bearing member or frame 41 by screws 69. The rear end of the rod 67 is threaded and receives a nut 70 that constitutes an adjustable abutment co-operating with the back of the extension 68 and connecting the tabulator with the frame 41 so that an actuation of the tabulator key 61 will swing said frame on its pivots 42, separating the pinion 38 from 100 the rack 35 when the tabulating mechanism 105 is operated.

Behind the main frame and its appurtenances as above described there is arranged an upright carriage structure adapted to hold the work sheet in a flat, taut condition vertically disposed, this carriage structure being adapted to travel or reciprocate for letter feeding transversely of the main frame. The bearings for the carriage structure may be of any character suitable 110 for such reciprocation and may be supported in any suitable way. In the present instance I have shown such bearings as secured to the main frame itself at the rear of the latter and while I prefer this construction, never- 115

120 125 130

theless various other ways of constructing and mounting the bearings of the reciprocating carriage may be employed.

As herein shown (see especially Figs. 1 and 2) the carriage supports comprise two horizontal guide rails 44 that are arranged one above the other, their inner or opposing faces being grooved. These rails are immediately behind and contiguous to the rear edges of the side plates 2. The upper rail 44 is secured near its ends by screws 71 to angular brackets 72 that are fixed to the inner faces of the side plates 2 in any suitable way, as by screws 73 and co-operating nuts 74. Two of these nuts co-operate with each screw 73, one nut being arranged outside the side plate 2 and the other inside and abutting against the bracket 72, the nuts exerting a clamping action. The lower stationary rail 44 is secured to the base frame 1 by screws 75. The base 1 projects slightly to the rear of the side plates 2 and the lower rail 44 rests on this projecting portion, thus enabling the screws 75 to be screwed downward through the rail and into the top of said projecting portion which has a broad lip or ledge. The stationary rails 44 are connected through roller bearings 76 with oppositely grooved guide rails 77 that are fixed to and caused to travel with the traveling carriage, designated as a whole by the numeral 78, as appears from Figs. 1, 2, 4 and 9, comprises two parallel angled uprights or bars 79 which are rigidly connected by a skeletonized cross plate or bar 80. The plate 80 comprises two triangular portions 81 connected at their apexes by an upright portion 82 which as appears hereinafter serves as a carriage stop arm. Interposed between the bases of the triangular portions 81 and the uprights 79 are washer plates 83. Screws 84 pass through the plates 83 into the end portions of the cross plate 80 and thence into the rails 77, thus securing the rails fixedly to the frame 78. Additional screws 85 passing through the parts 81 and 82 of the cross frame into the rails 77 assist further to secure said rails to the frame 78. The feed rack 35 with which meshes the gear wheel 36 and the escapement pinion 38, is arranged above the lower rail 77 and is secured to the cross plate 80 of the carriage by screws 85. Mounted on the carriage frame 55 78 is a platen which in the present instance I have shown as a rectangular metal bar 86 arranged transversely of the frame 78, being seated at its ends in grooves indicated at 87 formed in blocks 88 that are secured to the inner faces of the side walls of bars 79 by screws 89 and 90. The screws 89 are of the ordinary headed sort; the screws 90 are without heads and screwed through the bottom of the grooves 87 into the ends of 60 the bar platen 86, thus holding the platen in

fixed relationship to the carriage frame. Nuts 91 serve to set or lock the screws 90. The front or printing face of the flat or bar platen 86 is disposed slightly behind the front walls of the bars 79 and so that the 70 work sheets when in place on the carriage, as hereinafter described, may pass over the front vertical or printing face in a flat condition. The types on the type bars 7 co-operate with the front face of the bar platen 75 throughout its length as the carriage is letter spaced from right to left, one of the type bars being shown in printing position by dotted lines in Fig. 1. In other words the machine is of the class known as front-strike typewriting machines.

The main carriage 78 provides a support for a secondary carriage or paper controller which is mounted to slide vertically up and down on the main carriage. Said secondary 85 or sub-carriage is shown detached in Fig. 11 and is designated as a whole by the reference numeral 92. The sub-carriage 92 comprises two upright parallel bars 93 that are formed on their rear faces with rack teeth 94, these 90 rack bars being rigidly connected at their upper ends by a cross piece or bar 95, having rearwardly turned end portions 96. Arranged between said end portions and the upper portions of the bars 93 are bearing 95 plates 97 having rearward extensions or heads 98 at their tops. Screws 99 serve to secure the rack bars 93, plates 97 and cross bar 95-96 in rigid relationship. Mounted on the head portions 98 of the plates 97 are 100 the two parts 100 and 101 of a paper clamping device. The part 100 is a cross bar which is rigidly secured at its ends to the heads 98 while the part 101 is pivotally mounted on said heads in rear of the fixed 105 clamping bar 100, the part 101 bearing provided with pintles 102 which bear in holes in the heads 98. The pivoted bar 101 is cut out, as indicated at 101^a, so as to partly embrace the bearing portions of the heads 98 110 and so that the ends of said bar may be arrested by the tops of the extensions 98 which serve as limiting stops. When the clamp is operative the paper passes between the front face of the pivoted bar 101 and the rear face 115 of the fixed bar 100, the arrangement being such that a downward pull on the paper will serve to wedge it tightly between the clamping bars which thus provide a positive clamp. A finger piece 103 is secured to one end of 120 the pivoted clamping bar by which it may be swung into and out of operative position. This finger piece is angular so that the finger portion proper extends forward within convenient reach of the operator as will 125 be understood from Figs. 1 and 6. As best appears from the last mentioned figure, spring fingers 104, secured to the bottom of the clamping bar 100, extend rearward under the bar 101, co-operating with the rear 130

portion thereof as detents to hold said bar 101 in both its operative and inoperative positions preventing looseness and rattling. The inoperative or swung back position is shown by dotted lines in Fig. 6. In this position the finger piece 103 contacts with the under face of the adjacent head 98 to prevent overthrow. A severing blade 105 is vertically arranged above the bar 100 just forward of the clamping opening, said blade being secured to brackets 106 which are also suitably secured to the clamping bar 100. The upper sharpened edge of the blade 105 is thus suitably positioned to co-operate with the paper after it has passed through the clamp 100, 101, so that it may readily be severed by being drawn forward and downward against the blade 105. The slideable sub-carriage, paper controller or clamp carrier 92, when in place on the main carriage, has its side bars 93 just inside the side walls of the angular bars 79 and behind the front walls of said bars. The blocks 88 are cut out, as indicated at 107 to afford a passageway for the bars 93, and provide slide bearings for the sub-carriage or clamp carrier.

In order to control relative movements between the secondary or sub-carriage 92 and the main carriage 78, feeding mechanism or devices are provided comprising gear wheels or pinions 108 which mesh with the rack teeth 94, said gear wheels being arranged on the end portions of a shaft 109 mounted on the main carriage, the ends of the shaft being reduced as at 110 and bearing in the rearwardly extending portions of angular bearing plates 111 which are secured by headed screws 112 to the outer faces of the side walls of the carriage bars 79. The sub-carriage feeding devices comprising the racks 94 and gear wheels 108 are best shown in Figs. 1, 2 and 6-9. The left-hand gear wheel 108 (or, as viewed from the rear as in Fig. 2, the right-hand gear wheel) is clamped fixedly in place on the shaft 109 by a clamping nut 113 which is threaded on the outer end portion of said shaft and clamps the wheel against a flange or enlargement 114. There is a similar clamping nut 113 and flange 114 on the opposite end of the shaft, as illustrated more particularly in Figs. 7 and 8, but the construction is somewhat different, owing to the fact that the shaft-turning devices are associated with the gear wheel at the right. These shaft-turning devices comprise a ratchet wheel 115 which is secured against the shoulder 114 in any suitable way, as by soldering. The ratchet wheel is mounted on a plain portion 116 of the shaft between the flange 114 and a threaded portion 117 on which the gear wheel 108 is mounted. Confined between the ratchet wheel 115 and the gear wheel 108 and clamped by the nut 113 is a bearing ring 118 on which bears the annulus 119 of a pawl carrying arm 120 which extends rearward radially of the shaft 109 and at its outer end carries a headed shoulder screw 121, which provides a bearing for an angular pawl member 122 at the lower end of which is a tooth that is adapted for co-operation with the teeth of the ratchet 115, although normally separated therefrom. The pawl carrying arm 120 has a frictional engagement with the inner face of the ratchet wheel 115 being formed with a depression or seat 123 in which is arranged a friction spring 124. The coils of this spring tend constantly to expand and thus maintain a constant friction between the pawl carrying arm 120 and the ratchet wheel 115. In rear of its pivot 121 the pawl member 122 is pivotally connected at 125 with a twisted link 126 the lower end whereof is pivotally connected at 127 with a crank arm 128 that is fixed by a screw 129 to a rock shaft or line spacing member 130 that bears in a hood or housing 131 suitably fixed to the outer face of the right-hand carriage bar 79. As shown in the present instance the fixing means comprise screws 132, the rear screw screwing directly through the side wall of the bar 79 and the front screw through an angular bracket 133 which is screwed fast to the front wall of said bar 79. A spring 131^a is coiled around the rock shaft 130 within the housing and has one of its ends anchored thereto, the other end being secured to the rock shaft, the tendency of said spring being constantly to raise the crank arm 128 at the rear end of said rock shaft. The rock shaft 130 extends horizontally forward and terminates in a downwardly extending handle or finger piece 130^b which is conveniently located for manipulation by the operator, and provides both a line spacing handle and a carriage return key or handle, being adapted both to move the sub-carriage or clamp carrier upward step-by-step on the main carriage while the latter is stationary, and also thereafter, as the latter part of a single concurrent operation, to restore the main carriage and the devices mounted on it from left to right to begin a new line of writing. To limit the movements of the pawl 122 so as to restrict its action at each operation of turning the ratchet wheel 115 to an extent corresponding to a single ratchet tooth, stop devices are provided comprising an angular stop plate 134 screwed to the upper part of the right-hand carriage bar 79 and extending rearward between the ratchet wheel 115 and the gear wheel 108, the end portion of said stop plate 134 being so located as to co-operate with the upper face of the pawl carrier 120 to limit the upward swing of said carrier. A stop finger 135 is screwed fast to the carriage bar 79 and extends rearward across the path of the crank arm 128 130

to limit downward movement of said crank arm and consequently of the pawl 122. Detent devices are provided for co-operation with the line spacing mechanism to hold the sub-carriage or clamp carrier after each of the step-by-step upward movements on the main carriage. Said devices comprise a detent nose 136 that co-operates with the ratchet wheel 115, said nose being fixed 10 to a spring finger 137 screwed fast to the carriage bar 79. Said detent is controlled by a crank arm 138 that has a rounded free end contactive with the rear face of the spring finger 137. As will be understood 15 from Figs. 6 and 7 the crank arm 138 is mounted on the inner reduced end of a hollow stud 139, being clamped in place thereon by a headed screw 140 that is threaded into the bore of the stud. Mounted on the outer 20 reduced end of said stud is a horizontally disposed and forwardly extending crank arm 141 that is provided with a finger piece or release key 142, said crank arm being likewise secured to the stud 139 by a headed screw 143. Said stud bears in a hollow sleeve 144 that is fixed to the outer wall of the right-hand angle bar 79.

In operation, an actuation of the line spacing handle 130^a will rock the shaft 130, 30 swing down the crank arm 128, pulling down on the link 126, which in turn will swing the pawl member 122 on its pivot 121, causing its tooth to engage with the ratchet wheel 115. During this swinging movement of 35 the pawl member the carrier 120, which supports the pivot 121, will remain motionless because of its frictional connection through the spring 124 with the ratchet wheel 115. After the pawl 122 has engaged with the 40 ratchet wheel, however, further pulling movement on the link 126 will result in a turning movement of the pawl carrier 120 and of the ratchet wheel 115 about their common axis. This movement of course causes 45 a partial rotation of the shaft 109 and of the gear wheels 108, movement of the gear wheels being transmitted through the rack teeth 94 to the rack bars 93, resulting in an upward movement of the sub-carriage or clamp carrier 92 on the main carriage 78. This upward movement will be continued until the 50 parts are arrested by engagement of the crank arm 128 with the stop finger 135, the parts being so adjusted and proportioned 55 that the movement corresponds to a line space distance on the work sheet. It will be understood that after engagement of the crank arm 128 with the stop 135, further power applied to the line spacing handle 130^a 60 will be transmitted to the main carriage, which up to this time has remained stationary but which will now be returned towards the right on its bearings. On releasing the line space handle or key 130^a the 65 spring 131^a will become effective to restore

the rock shaft 130 and the connected train of devices, up to and including the pawl carrier 120 and the pawl member 122, to normal position. During this restoring operation the ratchet wheel 115 will be held 70 against rotation by the detent 136, the spring 131^a being strong enough to overcome the friction spring 124 which will slide over the inner face of the ratchet wheel 115. Successive operations of the line spacing handle 75 will result in successive step-by-step upward movements of the sub-carriage on the main carriage and consequently in line space advances of the paper or work sheet controlled by the sub-carriage. Pressure on the release 80 key 142 is effective to swing the arm 138 forward against the spring finger 137, which as it is pushed forward will throw the detent 136 out of the ratchet wheel 115, releasing the train of mechanism of which said ratchet 85 wheel is a part and permitting the sub-carriage 92 to move continuously downward under the influence of the force of gravity. At this time, as will be subsequently explained more in detail, the clamp on said 90 sub-carriage is open so that the work sheet is free from its control. The downward movement of the sub-carriage may continue until it is arrested by engagement of the right-hand part 96 with the top edge of the stop 95 plate 134, as shown in Fig. 6.

In order to control and guide the work sheet, whether single or multiple in character, below the platen, there are provided devices at the lower part of the main carriage comprising a pair of guide or presser bars which are normally spring pressed towards each other, their effect being to act as a drag on the work sheet near its lower end as it is controlled and drawn upward by 100 clamp 100—101 near its upper end, with the result that the work sheet is maintained taut and flat and the usual transverse creases of 105 long fan-fold strips or webs are effectively smoothed or ironed out and prevented from 110 obstructing the easy upward advance of the work sheet. Referring especially to Figs. 1, 2, 5, 5^a, 9 and 14, the guide or presser bars which are arranged transversely of the carriage are designated as 145 and 146. These 115 bars are generally square in cross section but their bottom corners are rounded to facilitate entering the work sheets between them. The bar 145 is seated in the angles of the right angled bars 79 at their lower ends and 120 is suitably fixed to said bars as by pins 147 driven through them and into the ends of the bar 145, which is thus secured to the main carriage. The bar 146 is arranged contiguous to the rear face of the bar 145 and is 125 provided at its ends with outwardly extending pins or pintles 148 which bear in holes in the lower ends of swinging arms 149 pivoted at 150 to the inner faces of the side walls 130 of the angle bars 79. Wire springs 151 se-

cured to the outer faces of said side walls engage with said pins and tend constantly to maintain the guide bars in spring pressed engagement with each other. The mounting of the bar 146 affords self adjustment of it according to the character of the work sheet with which it engages. Hand controlled devices for overcoming the springs means 151 and separating or spreading the 10 presser bars, as indicated by dotted lines in Fig. 5^a, to facilitate the insertion and adjustment of the work sheets, comprise a rock shaft 152 mounted on brackets 153 screwed to the outer faces of the angle bars 79 and depending therefrom. Mounted on said rock shaft outside said angle bars are cam plates 154 having hubs 155 that are fitted over and suitably fixed to the rock shaft. Outside the 15 right-hand cam plate a crank arm 156 is arranged on the rock shaft, said crank arm having a hub 157 that fits over and is fixed to the rock shaft. On the free end of said crank arm 156 is a finger piece 159 by which the rock shaft and the cam plates are controlled. Each cam plate 154 is formed with 20 a cam surface 154^a terminating in dwells 154^b and 154^c, the cam surface or edge and the dwells co-operating with the projecting pins 148. When the pins 148 are opposite the dwells 154^b the springs 151 are effective to maintain the pressure bars 146 and 145 in effective relationship. At this time the crank arm 156 is horizontally disposed, as shown in Figs. 1 and 2. By pressing down on the 25 finger piece 159 and swinging the crank arm 156 downward the cam faces 154^a are caused to act on the pins 148, being so shaped as to force said pins rearward against the pressure of the springs 151, thus swinging the arms 149 rearward and carrying the bar 146 bodily rearward to the dotted line position of Fig. 5^a. In this position said bar 146 is maintained by the co-operation of the dwells 154^c with the pins 148, the bar being in effect 30 locked so that the operator may let go the key 159 and have both hands free to manipulate the work sheet. The latter is passed upward between the presser or guide bars 145 and 146 and to facilitate its proper insertion, side 35 gages or guides are provided comprising angled plates 160 which are secured by screws 161 to the bar 146 and are of such width that they bridge the gap or space between the bars even when they are separated, 40 said guides moving with the bar 146 across said space. After the work sheet has been inserted and passed upward over the front face of the platen and brought within the control of the clamp 100, 101 above the 45 platen, and after the short carbon sheets are adjusted as hereinafter explained, the presser bars may be closed by swinging the finger piece 159 back toward normal position, the bars then exerting a suitable spring pressure 50 on the work sheet throughout its width.

It may here be noted that the tabulator stop member 64 that is mounted on the main frame as heretofore described, is adapted to co-operate with the downwardly projecting stop faces of column stops 162 that are 70 adjustably mounted on a column stop bar 163 of ordinary construction, toothed on its top and bottom faces, and arranged just forward of and parallel with the presser bar 145 (see Figs. 1, 5, 5^a, 9 and 14). Said 75 column stop bar is suitably supported on the main carriage as by angled brackets 164 which are secured by screws 165 to the front faces of the carriage bars 79 near their lower ends. The column stop bar is secured to 80 the under faces of the forwardly projecting horizontal portions of said brackets by headed screws 166.

There is also mounted on the main carriage a second sub-carriage or paper controller which serves as a carbon carrier, having mounted on it detachable carbon holders which carry short sheets of carbon paper or other suitable transfer medium that are adapted to be interleaved with a plurality 90 of sheets of paper or the folds of a fan-fold work sheet. This carbon carrier or sub-carriage is designated as a whole by the numeral 167, being shown detached in Fig. 10. Other views which illustrate the carbon carrier 95 and its feeding mechanism are Figs. 1, 2, 3, 4, 6, 12 and 13. The carbon carrier 167 comprises a cross bar 168 terminating in two cross pieces or heads 169, from each of which projects rearward a pair of pointed 100 pins or carrying devices 170. The cross bar 168 serves to connect two vertically disposed rack bars 171, the heads 169 being screwed fast to the rack bars by screws 172. Each rack bar 171 is formed on its front face 105 with a series of rack teeth 173 providing racks which extend throughout the lengths of the bars. The outer side faces of the bars are formed with longitudinal grooves 174, these grooves slidably engaging with 110 the inner edges of the front walls of the angle bars 79 which provide trackways for the carbon carrier. The bars 171 extend upward from the cross bar 168, and the bar platen 86 is provided with cutouts 86^a 115 to afford passage ways for said bars 171. Limit of upward movement of the carbon carrier is determined by contact of the heads 169 with the under side of the bar platen. The carbon holders may be angular members 120 of thin metal comprising each a horizontal bar-like body portion 175 and a short vertically disposed arm 176 integral with the body portion and extending vertically downward from one end thereof and at right angles thereto. The vertical arm 176 is formed with holes spaced apart to fit over the associate pair of pins 170. The construction readily enables the holders to be slipped 125 on and off the pins, thus connecting them 130

with and disconnecting them from the carbon carrier. Short carbon sheets or strips 177 are attached to the bars 175 in any suitable way. For example the lower horizontal edge portion of the carbon sheet may be folded over and pasted to the body of the carbon sheet, thus providing a passage way into which the bar 175 may be passed. Each sheet extends upward from its holder, it being understood that the holders are arranged in alternation along the carbon carrying pins and in number corresponding to the work sheets or surfaces to be written on back of the first sheet, which latter is printed from the regular ribbon of the machine.

Means are provided for communicating a slow upward feeding movement to the carbon carrier or slide frame on the main carriage frame so as to enable said sheets, although they are comparatively short, to be used in writing a considerable number of bills. The feeding means comprise a feed shaft 178 arranged transversely of the main carriage, said shaft bearing near its ends in bearing blocks 179 secured by screws 180 to the front faces of the carriage bar 79. The shaft 178 may be reduced slightly near its middle to clear the upper end of the upright bar 82 which passes in front of it. Said shaft is formed with teeth providing pinions 181 that mesh with the rack bars 171 of the carbon carrier. These pinion portions 181 are larger in diameter than the body of the shaft 178 and are arranged inside the bearing blocks 179, being adapted to contact with the inner faces thereof to prevent endwise displacement of the shaft. Fixed to the outer right-hand end portion of said shaft by a set screw 182 is an elongated hub 183 terminating in a knurled button or finger piece 184, which is operative to turn the shaft 178 and move the carbon carrier up and down at will when desired. Preferably however, the carbon carrier is fed automatically step-by-step in an upward direction by means co-operative with the left-hand end portion of said shaft 178. Said means comprise a worm gear or wheel 185 having a hub 186, the worm wheel being loosely mounted on the end portion of the shaft 178 projecting beyond the left-hand bearing block 179 by devices shown in detail in Fig. 13. The worm wheel or pinion and its integral hub are confined between a flange 187 rigid with the shaft 178 and a thimble-like part comprising a flange 188 and a hub 189, which hub fits with a tight frictional fit over the end of the shaft. The hub 186 of the worm gear has a bearing engagement with the hub 189 of the thimble. The worm gear or wheel is counter sunk, as indicated at 190, to receive the head or flange 188 of the thimble, between which and the worm wheel is inserted a friction spring 191. The friction spring has four radial

cuts 192 (Fig. 12) which divide it into four leaves that are so twisted as to provide frictional resistance when the spring is compressed. Such compression is applied by a headed screw 193 whose shank is threaded into the outer end of the shaft 178, the head of said screw being adapted to force in the head 188 of the thimble and compress the spring 191 more or less. This enables the amount of friction between the gear wheel or worm wheel and the shaft 178 to be regulated with nicety since while the thimble may be moved lengthwise relatively to the shaft by means of the screw 193, nevertheless said thimble fits so tightly on the shaft 178 as to be in effect a part of it during turning movements. The construction is such that while the worm wheel may be held positively and the shaft 178 may be at the same time turned by overcoming the friction due to the spring 191, yet if the worm wheel be rotated its rotative movement will be communicated to the shaft 178 by reason of the frictional connection between the two parts. The worm wheel constantly engages with a worm device comprising an upright shaft 194 provided with an endless screw or spiral 195 that meshes with the teeth of the worm wheel. The spiral is connected by an upwardly extending hub or neck 196 with a ratchet wheel 197, and above the ratchet wheel is a cap or head 198 which is connected with the ratchet wheel by a narrow neck 199, the three parts 195, 197 and 198 being rigid with each other, and a cross pin 200 driven through the neck 196 and the shaft 194 serving to connect said three parts fixedly with said shaft. The latter bears in a sleeve or bearing block 201 having end tabs that are secured by screws 202 to the outer face of the left-hand carriage bar 79. A headed screw 203, threaded into the bottom end of the shaft 194, prevents upward displacement of said shaft. The teeth of the ratchet wheel 197 are constantly engaged by the free end of a spring finger or detent 204 secured by screws 205 to the outer face of the carriage bar 79. This detent prevents the ratchet wheel and worm gearing from turning accidentally and maintains the connected carbon carrier in adjusted positions. The ratchet wheel 197 is turned to advance the carbon carrier step-by-step through a pawl member 206 provided with several teeth adapted to engage with the ratchet teeth. The pawl member is pivoted at 207 to the under face of a horizontal plate-like end or head 208 of a pawl carrier which further comprises a body or bar portion 209 turned upward at right angles to the part 208 and extending rightwardly at the front side of the carriage, terminating in an upstanding contact nose or stop 210. Near its right-hand end the pawl carrier is formed with a slot 211 which bears on a headed shoulder 180

screw 212 that is threaded into the rear upper end of the upright carriage bar or stop arm 82. This provides a slidable bearing for the right-hand end of the pawl member.

5 At its left-hand end the pawl member bears on the upper face of the ratchet wheel 197, and to this purpose the head 208 is cut out to provide a slot 213 which embraces the neck 199, the pawl member being thus loosely confined between the ratchet wheel 197 and the cap 198. A coiled spring 214, anchored at one end to the upright portion 82 and at 10 its other end to a pin 215 on the pawl member; tends constantly to draw said pawl member towards the right on the carriage and to maintain it in a normal position of arrest. Such position is determined by an adjustable screw stop 216 which is threaded into a twisted eye or lug 208^a on the head 208 and is adapted normally to contact with the outer face of the carriage bar 79. A pawl spring 217 is anchored to a pin 218 extending downward from the head 208, the other end of said spring being connected to 15 a pin 219 on the pawl 206. The spring 204 is afforded a passage downward through the slot 213 for engagement with the ratchet wheel 197.

The pawl carrier 208—209 is actuated automatically during the return movements of the carriage through a margin stop 220 which projects downward into the path of the nose or stop 210, as well as into the path of the end of the upright stop arm 82. Said 20 margin stop 220, together with a similarly constructed carriage stop or line stop 221 is slidably and adjustably mounted on a toothed stop bar 222 that is arranged between the upper part of the main frame and 25 the carriage, being provided near its ends with elongated slots 223 that are engaged by shouldered screws 224 threaded into the frame lugs 10. The carriage stops 220 and 221 are of any suitable construction and are 30 provided respectively with finger pieces 220^a and 221^a by which they may be adjusted lengthwise of their support 222 to vary the extent of carriage movement and consequently of the lines of writing. The movement 35 of the carriage towards the right is determined by contact of the upper end of the arm or upright portion 82 which serves as a movable carriage stop with the margin stop 220, while movement towards the left to end 40 the line of writing is regulated by engagement of said stop arm 82 with the end stop 221. The end of the line is reached following the three or four step-by-step movements necessary, after engagement of the arm 82 45 with the stop 221, to move the stop bar 222 longitudinally leftward until the ends of slots 223 come in contact with the screws 224. The carriage having been arrested at the end of the line is restored from left to right 50 and as it nears the end of its return move- 55 ment the nose 210 will contact with the margin stop 220 and will move the stop and its stop bar 222 towards the right until the parts are arrested by contact of the opposite or left hand ends of the slots 223 with 60 screws 224. After such arrest of the stop bar the further slight movement that the carriage will undergo before being finally arrested by engagement of the stop arm 82 65 with the margin stop 220 will be effective on 70 the pawl carrier 208, 209 to slide it leftward (or as viewed from the rear rightward) in its bearings, overcoming the spring 214 and causing the pawl 206 acting on the ratchet wheel 197 to turn said ratchet wheel, 75 this movement being transmitted to the worm gearing 195, 185, and thence to the shaft 178 and pinions 181 which will actuate the racks 173 and move the carbon carrier 167 slightly upward. The extent of this 80 movement is of course determined by the amount of turning communicated to the ratchet wheel 197 from the pawl 206, and this in turn is dependent on the position from which the pawl starts this position being regulated by the adjustment of the screw stop 216 whose inner end normally contacts with the face of the carriage bar 79. As 85 soon as the carriage following its return starts to move towards the left the spring 214 will become effective and through its action the pawl carrier 208, 209 and its pawl will be restored to normal position, as in Fig. 2, with the stop 216 in contact with the carriage bar 79. Repetition of the described 90 operations will result in successive step-by-step advance movements of the carbon carrier such movements being extremely slight due to the worm gearing, so that the carbon 95 is fed very slowly.

100 Means are provided for releasing the main carriage 78 and the parts supported on it from the control of the letter feeding or escapement mechanism, this being accomplished either by a hand operation or automatically when the tabulating devices are 105 operated. Said means in the present instance comprises, as illustrated in Figs. 1, 2, 9 and 14, a releasing bail composed of a cross bar 225 and crank arms 226 connected 110 to the ends of the bail and pivoted at 227 to the outer faces of the carriage bars 79. The crank arms normally extend upward and forward and the bail cross bar 225 passes in front of the carriage bars 79 and 115 120 transversely of the carriage, lying normally just back of and above the extension 68 on the swinging or rocking frame 41. The bail is held in this position by a coiled spring 228 connected to the left-hand crank arm 125 226 and also to a pin 229 projecting from the bearing block 201. A link 230 is pivotally connected at 231 to said arm 226 below its pivot 227 and extends upward outside the left-hand carriage bar 130

79, being pivotally connected at its upper end at 232 to the rearwardly extending arm of a release lever 233. The latter is pivoted at 234 to the carriage bar 79 and extends horizontally forward, terminating in a release key 235. When depressed said release key is effective to pull up the link 230 and swing the release bar downward into engagement with the extension 68, causing the upper 10 portion of the frame 41 to swing forward about its pivots 42 and separating the feed pinion 38 from the feed rack 35, thus releasing the main carriage from the control of its letter feeding mechanism and enabling the 15 operator to move said carriage freely towards the left by hand. This forward swing of the frame 41 does not affect the arm or link 67, which is operated by the tabulator key, the only effect being to slide the extension 68 forward along said rod or arm 67 and away from the nut or abutment 70. On releasing the key 235 the release bail and connected devices will be restored to normal position by the spring 228, the parts being 20 arrested by contact of the link 230 with a pin stop 236 projecting laterally from the carriage bar 79. Concurrently the frame 41 will be swung back by the springs 45 causing the pinion 38 to re-engage with the 25 rack 35.

When the tabulator key 61 is depressed it is effective to swing the lever arm 58 downward and the lever or stop arm 64 upward into the path of the downwardly projecting column stops 162, while concurrently the arm 65 will be swung forward, pulling the arm or link 67 and causing the nut 70, acting against the extension 68, to swing the frame forward to release the carriage. This 30 operation of course will not affect the release bail 225, 226. As a consequence of a depression of the tabulator key, the carriage is released and will run down towards the left until arrested by the engagement 35 of the proximate column stop with the frame stop 64. After such arrest pressure is withdrawn from the tabulator key and the parts will be restored to normal position, the train of tabulating devices by the spring 62 and 40 the escapement devices by the springs 45.

In order to facilitate the insertion and adjustment of the work sheet or sheets and in cases where it is desired to interleave carbon sheets, the machine as a whole, comprising both the main frame and its parts and also the carriage behind the main frame, is so mounted that it may be swung downward and forward, affording access to the carriage from the front of the table. Other 45 means of affording ready access to the carriage to facilitate the adjustment of a work sheet or sheets thereon will suggest themselves to those skilled in art. In the present instance, as stated, this purpose is 50 achieved by a bodily swinging movement of

the main frame and carriage together, and this operation is facilitated by mounting the carriage on a skeletonized support or stand of special construction, said stand or table being illustrated in Figs. 1 and 1^a. The 55 table or stand which is made of hollow tubing, the parts being suitably connected together, comprises two parallel horizontal bars 237 and 238, the latter being behind and somewhat lower than the bar 237. The 60 bars 237 and 238 which are at the upper part of the stand are connected at their ends to the side portions thereof, said side portions each comprising a top cross bar 239 and two depending legs 240, the four legs 65 being suitably braced or connected near their lower ends, as by cross bars 240^a and a rear bar 240^b. The two legs 240 at the left end of the table are extended upward and provide a support for a table top 241, which is conveniently located to receive the work sheets, etc. An additional short leg 242 secured to the front bar 237 near its left end assists to support the table top 241, the latter in effect having three legs or foot portions 70 triangularly disposed.

The typewriting machine is supported between the table ends by means of the front and rear bars 237 and 238. Secured to the sides of the main frame 1 by screws 243 are 75 plates 244 extending downward and terminating in half-eyes 245 which engage with and are supported on the bar or rod 238. Curved pieces or complementary half-eyes 246 pass around the under side of the rod 238 80 and are detachably connected with the parts 245, as at 247 and 248. The connection 247 is a pivotal connection and the connection 248 is a detachable screw by unscrewing which the eye part 246 is released and allowed to 85 drop downward about the pivot 247, thus affording a ready disconnection of the machine from the bar 238. It will be understood that said eyes provide a pivotal connection of the machine with the frame or 90 table, enabling the machine as a whole to be swung or rotated pivotally about the axis of the rod 238 as a center. Stop pins 238^a projecting upward from the rod 238 just inside the parts 245 prevent endwise 95 displacement of the machine along the rod 238. The machine is held normally in horizontal relationship with the table by a latching device that is supported on the front bar 237, said device being in the form 100 of a spring pin or plug comprising a cylindrical engaging portion 249 which bears in a hole in the rod 237 and is provided with a forwardly extending stem 250 of 105 smaller diameter, said stem bearing in a small hole in front of the rod and being provided with a knurled finger piece 251 by which the latch or locking pin may be 110 manipulated. A wire spring 252 is coiled around the stem 250 within the bore of the 115

120 125 130

rod 237, said spring abutting against the inner face of the rod at one end and against the front end of the pin 249 at the opposite end, and tending constantly to project said pin rearward and into engagement with an eye 253 secured by screws 254 to the front wall of the base 1 and projecting downward therefrom. By pulling forward on the finger piece 251 the pin or plug 249 is withdrawn 10 from the eye 253, and the machine as a whole may then be allowed to swing forward and downward between the two bars 237 and 238 until it reaches the position illustrated by the dotted lines in Fig. 15. 1. The machine will be held in this dotted line position by a flexible connection or chain 255 which is anchored at 256 to the bar 237 and at its opposite end is secured to a screw 257 that is threaded into the side 20 of the base 1. Thus swung forward and held, the carriage is conveniently disposed to receive the work sheet or sheets.

In the present instance the work sheet illustrated is a multiple work sheet being what is commonly known as a fan-fold sheet, and is designated as a whole by the reference numeral 258. The fan-fold sheet 258 is of the character employed by the Dominion Steamship Company for freight billing and comprises six plies or folds. The first or outer ply which receives imprints directly through the ribbon of the machine is the "Local way bill"; the second ply is the "Freight bill"; the third ply is the "Arrival notice"; the fourth ply is the "Delivery receipt"; the fifth ply is the "Prepaid freight bill"; and the sixth ply is the "Station record." As is usual, the plies contain a succession of printed blanks, the printed 30 blanks on each ply being identical and the blanks being usually some five or six inches in length. Much of the matter to be written in the blanks on the different plies is identical, so that all the blanks may be largely 40 filled in at one writing on the typewriting machine. The fan-fold multiple work sheet or strip comprising the six plies or folds, more or less, is of considerable length, some fan fold strips being as lengthy, for example, 45 as 25 feet and containing on each fold or ply a large number of printed blanks. For convenient handling the six-ply strip is folded transversely at intervals of, say, eight inches, and after the leading end has been fed into 50 the machine the folded strip may be placed in a basket or other suitable receptacle behind the machine. With the machine swung forward and the carriage uppermost, as in the dotted-line position of Fig. 1, the operator 55 pushes the key 159, opening the presser bars 145 and 146 so that the leading end of the fan-fold strip or sheet 258 may be conveniently passed up between them, being restricted to the proper position lengthwise of 60 said presser bars by the vertical contact faces of the side guides or gages 160. Thence the work sheet is drawn upward and over the front or working face of the platen 86 and between the clamping jaws 100 and 101, the clamp having been opened by swinging 70 the pivoted bar 101 into the dotted line position of Fig. 6. The clamp may then be closed to grip or clamp the upper edge portion of the fan-fold sheet. Next the necessary number of carbon holders 175, 176 (five 75 in the present instance as diametrically illustrated in Fig. 4) are slipped on the carrying pins 170, two holders on the left-hand set of pins and three on the right-hand set, and the short carbon sheets 177 carried by said 80 holders are interleaved with the plies of the fan-fold sheet, as illustrated in said figure. It will be understood that the carbon sheets 177 extend upward between the fan folds from their supporting bars 175 which extend 85 between and transversely of said folds or plies. The carbon carrier 167 having been drawn down to its lowermost position in which the ends of the cross heads 169 contact with the upper surface of the presser 90 bar 145, the upper edge portions of the carbon strips will be about opposite the printing line on the platen. The presser bar having been closed by pulling forward the finger piece 159 the operator may next swing the 95 whole machine upward on the supporting bar 238 and may lock or secure the machine in its normal position by causing the pin or plug 249 to engage with the eye 253 on the front of the machine frame. Assuming that 100 the clamp carrier 92 has been lowered to its initial position, as illustrated in Fig. 6, and that in this position the blank for the first item that is to be duplicated on all of the folds is opposite the platen, then the carriage 78 should be moved widthwise on its 105 bearings to bring opposite to the printing point the beginning of the blank that is to be filled in. As each type bar 7 is actuated the type impression will be made on the 110 front ply or fold of the fan-fold sheet through the ribbon 25 of the machine and simultaneously will be duplicated on the other five plies behind the front ply through the interleaved carbon sheets. At the end 115 of the first line of writing the line spacing handle 130^a is actuated advancing the clamp carrier 92 upward on the main carriage a line space distance and drawing the multiple fan-fold strip or sheet through and between the presser bars 145 and 146, thus providing 120 a drag which keeps the work sheet taut and smooth. At the end of the line spacing advance the crank arm 128 contacts with the stop 135 so that further pressure on the line spacing handle 130^a results in a lateral movement of the entire carriage structure 125 towards the right to begin a new line of writing. Just before the end of the line is reached the nose 210 will contact with the 130

margin stop 220 as has been explained, resulting in an automatic feeding movement being communicated to the carbon carrier 167 which will be moved slightly upward, 5 advancing the carbon sheets between the folds of the fan-fold sheet. It will be observed that the feeding movements of the two sub-carriages 92 and 167, while parts of a concurrent operation resulting from a single actuation of the line spacing handle, are nevertheless independent of each other; and it will also be noted that the said feeding movements vary in extent, the line spacing movement of the paper being much the greater; and these two line spacing movements are independent of the lateral movements communicated to the carriage for letter feeding, tabulating runs, and return movements to begin new lines. The operations above outlined are continued until the clamp carrier has been line spaced upward sufficiently to enable a completely written bill and its duplicates to be fed out of the machine, whereupon the clamp carrier may be retracted. Prior to retracting the clamp carrier the clamping bar 101 is thrown back, opening the clamp, and then the release key 142 is depressed, releasing the clamp feeding mechanism and permitting the clamp carrier to drop downward under the influence of gravity. Said clamp carrier may be arrested just below the completed bill and may then be closed, after which the completed bill and its duplicates are torn off and the plies separated for distribution in accordance with the requirement of the business. This retraction of the clamp carrier and severance of the completed multiple bill do not affect the carbon carrier, which does not reach the limit of its upward movement, owing to its slow worm feed, until a large number of bills have been completely written and torn off.

While I have outlined above the use of the invention with one form of work sheet it will be understood that the invention may of course be employed in collating and in various styles of typewritten work. Also it is to be understood that various changes in construction may be made, and that parts of the invention may be employed without other parts, all without departing from my invention.

What I claim as new and desire to secure 55 by Letters Patent, is:—

1. In a typewriting machine, the combination of a type bar supporting segment permanently inclined to the vertical, type bars mounted on said segment, a flat platen, an 60 upright platen carriage arranged behind said segment, type actuating devices for causing said type bars to strike against the front face of said platen, and means for facilitating access to said platen carriage for 65 the purpose of adjusting paper thereon.

2. In a typewriting machine, the combination of a main frame, type bar mechanism on said main frame, ribbon devices including ribbon spools having their cups stationary on said main frame, carriage bearings at the 70 rear of said main frame, a vertical paper carriage co-operative with said bearings and extending from the lower part of said main frame to a position above said main frame, and a platen on said carriage against the 75 front face of which the type bars are adapted to strike.

3. In a typewriting machine, the combination of a main frame, type bar mechanism on said main frame, ribbon devices including 80 ribbon spools having their cups stationary on said main frame, and means for supporting a work sheet in a flat vertical condition in rear of said main frame and for feeding said work sheet both transversely of the machine and upwardly past the printing point.

4. In a typewriting machine, the combination of a main frame, type bar mechanism on said main frame, ribbon devices including 90 ribbon spools having their cups stationary on said main frame, and means for holding a fan-fold work sheet in a substantially vertical plane behind said main frame, said means including a guide provided with a variable opening.

5. In a typewriting machine, the combination of a main frame, type bar mechanism on said main frame, ribbon devices including ribbon spools having their cups stationary on said main frame, an upright carriage arranged behind said main frame for a fan-fold work sheet, means for feeding said carriage step-by-step for letter spacing, and means for guiding and feeding said fan-fold sheet upward from line to line including a guide provided with a variable opening.

6. In a typewriting machine, the combination of a main frame, type bar mechanism on said main frame, ribbon devices on said main frame, means for holding a fan-fold work sheet in a substantially vertical plane behind said main frame, means for feeding said fan-fold sheet, and means for independently feeding carbon sheets interleaved 11 with the folds of said fan-fold sheet, said carbon-sheet-feeding means comprising devices for preventing the carbon sheets from dropping out of place through gravity.

7. In a front strike typewriting machine, 12 the combination of a type bar segment, key operated rearwardly striking type bars thereon, a vertically disposed carriage constructed to hold paper in a flat upright condition and arranged behind said segment and capable of transverse letter feeding movements, a platen on said carriage, and means for affording access to said carriage at its rear side to facilitate the adjustment 13 of paper thereon.

8. In a front strike typewriting machine, the combination of a type bar segment, key operated rearwardly striking type bars thereon, a vertically disposed carriage arranged behind said segment and capable of transverse letter feeding movements, a platen on said carriage, and means for moving said carriage at an angle to the direction of letter feeding movement to bring said carriage to a position for facilitating the initial adjustment of the paper.

9. In a front strike typewriting machine, the combination of a type bar segment, key operated rearwardly striking type bars thereon, a vertically disposed carriage arranged behind said segment and having transverse letter feeding movement, a flat platen on said carriage, paper controlling devices arranged on said carriage both above and below said flat platen, and means for affording movement of said carriage in a direction at right-angles to the direction of letter feeding movement to facilitate the adjustment of paper, the paper being arranged in a flat condition and held taut by the said paper controlling devices.

10. In a front strike typewriting machine, the combination of a type bar segment, key operated rearwardly striking type bars thereon, a vertically disposed carriage arranged behind said segment and having transverse letter feeding movement, a platen on said carriage, and means for affording a movement of said carriage and said type bar segment to bring the rear side of the carriage close to the operator thereby permitting the adjustment of paper on said carriage.

11. In a typewriting machine, the combination of an upright carriage frame, stationary carriage rails, roller bearings for connecting the lower portion of said carriage frame with said rails, a type bar segment arranged forward of said carriage frame, rearwardly striking type bars on said segment, a platen on said carriage frame, key actuated type bars on said segment co-operative with the front face of said platen, and means for affording a forward swinging movement of said carriage frame to bring its rear side closer to the operator thereby facilitating initial adjustment of the paper on said carriage and over the printing face of the platen.

12. In a typewriting machine, the combination of a carriage, letter feeding devices therefor, two bodily movable carriers on said carriage, and means for advancing said carriers independently of each other on said carriage.

13. In a typewriting machine, the combination of a carriage, letter feeding devices therefor, a platen on said carriage, a material controller on said carriage, means for moving said material controller bodily step-

by-step on said carriage transversely of the letter feeding movement thereof, and a second material controller on said carriage independent of said first recited material controller.

14. In a typewriting machine, the combination of a carriage, letter feeding devices therefor, a platen on said carriage, a material controller on said carriage, means for moving said material controller bodily step-by-step on said carriage transversely of the letter feeding movement thereof, a second material controller on said carriage, and means for moving said second material controller step-by-step relatively to said carriage.

15. In a typewriting machine, the combination of a main carriage, means for feeding said carriage step-by-step, two secondary carriages mounted on said main carriage, and means for feeding said secondary carriages step-by-step relatively to said main carriage and independently of each other.

16. In a typewriting machine, the combination of a carriage, letter feeding devices therefor, two carriers on said carriage, and means for moving said carriers bodily upward in a substantially vertical plane independently of each other.

17. In a front strike typewriting machine, the combination of a platen, a platen carriage, letter feeding devices therefor, rearwardly striking type bars having a stationary support and co-operating with the front face of said platen, two carriers on said carriage, and means for moving said carriers bodily upward in a substantially vertical plane independently of each other.

18. In a typewriting machine, the combination of a carriage, letter feeding devices therefor, two carriers on said carriage, means for moving one of said carriers step-by-step, and means for moving the other of said carriers step-by-step independently of the first carrier.

19. In a typewriting machine, the combination of a carriage, a platen, and means for holding a work sheet in a substantially vertical plane opposite said platen, said means comprising paper guiding devices below the platen and paper feeding devices above the platen adapted to draw the paper over and past said guiding devices.

20. In a typewriting machine, the combination of a carriage; a platen; means for holding a work sheet in a substantially vertical plane opposite said platen, said means comprising a holder below said platen and a second holder above said platen; and devices for effecting relative movement between said holders.

21. In a typewriting machine, the combination of a carriage; a platen; means for holding a work sheet in a substantially ver-

tical plane opposite said platen, said means comprising a holder below said platen and a second holder above said platen; and devices effective on one only of said holders to advance the work sheet relatively to the other holder.

22. In a typewriting machine, the combination of a carriage; a platen; means for holding a work sheet in a substantially vertical plane opposite said platen, said means comprising a holder below said platen and a second holder above said platen; and devices operating automatically to effect relative step-by-step movements between said holders.

23. In a front strike typewriting machine, the combination of a platen carriage; a platen; type bars having a stationary support and striking rearward against said platen; means for holding a work sheet in a substantially vertical plane opposite said platen, said means comprising a holder below said platen and a second holder above said platen; and devices operating automatically to effect relative step-by-step movements between said holders.

24. In a typewriting machine, the combination of a carriage, a platen, and means for holding a work sheet in a substantially taut, flat condition opposite said platen, said means comprising a positively operating clamp at one side of said platen and a paper presser device at the opposite side of said platen, the paper as it is fed advancing relatively to said presser device.

25. In a typewriting machine, the combination of a carriage, a platen, and means for holding a work sheet in a substantially flat and taut condition opposite said platen, said means comprising a positively operating feeding device at one side of said platen, and two presser bars between which the paper passes at the opposite side of the platen, the paper as it is fed advancing relatively to said presser bars.

26. In a typewriting machine, the combination of a carriage, a platen, and means for holding a work sheet in a substantially vertical plane opposite said platen, said means comprising a positively operating feeding device above the platen, a pair of bars between which the paper passes below the platen, and spring means for insuring relative pressing movement between said bars, the paper as it is fed advancing relatively to said pair of bars.

27. In a typewriting machine, the combination of a carriage; a platen; means for holding a work sheet in a substantially flat condition opposite said platen, said means comprising a positively operating clamp at one side of said platen and a paper ironing device at the opposite side of said platen; and devices for bodily moving the clamp step-by-step.

28. In a typewriting machine, the combination of a carriage, a platen, two parallel devices extending the full width of the work sheet and between which the work sheet is pressed, and devices at the opposite side of the platen effective to exert a pull on the work sheet, the effect being to maintain the work sheet taut and flat against the platen.

29. In a typewriting machine, the combination of a carriage; a platen; and means for holding a work sheet in a substantially taut flat condition opposite said platen, said means comprising two parallel devices extending the full width of the work sheet and between which the work sheet is pressed, and devices at the opposite side of the platen for drawing the work sheet line space distances through said parallel devices.

30. In a typewriting machine, the combination of a platen, a pair of co-operating spring pressed controllers between which the work sheet passes, and means at the opposite side of the platen for drawing the work sheet between said controllers, said controllers exerting a drag on the work sheet and tending to iron out creases as the work sheet passes through them.

31. In a typewriting machine, the combination of a platen, a pair of co-operating presser bars, means for separating said bars at will to facilitate the introduction of a work sheet, means for maintaining a spring pressed relationship between said bars, and means at the opposite side of the platen for drawing the paper over the platen and between said bars, the latter exerting a drag on the paper which tends to keep it in a flat condition as it passes over the platen.

32. In a typewriting machine, the combination of a platen, a pair of co-operating presser bars, devices for pressing the bars together, means for overcoming said devices and separating said bars at will to facilitate the introduction of paper, a side gage for the paper, and means for drawing the paper past the bars when they are closed.

33. In a typewriting machine, the combination of a carriage; a platen; means for holding a work sheet in a substantially vertical plane opposite said platen, said means comprising a positively operating clamp above the platen and a pair of spring pressed bars between which the paper passes below the platen; and step-by-step devices for moving said clamp upward to feed the paper over the platen and draw it between the spring pressed bars while they remain stationary.

34. In a typewriting machine, the combination of a carriage; a platen; a clamping device at one side of said platen; and a paper controlling device at the opposite side of said platen, said clamping device comprising a frame movable on said carriage, a clamping bar rigid on said frame, and a

- co-operative clamping bar pivoted on said frame, the paper being advanced over and relatively to said controlling device as it is fed by said clamping device.
- 5 35. In a typewriting machine, the combination of a carriage; a platen; a clamping device at one side of said platen; a paper controlling device at the opposite side of said platen, said clamping device comprising a frame movable on said carriage, a clamping bar rigid on said frame, and a co-operative clamping bar pivoted on said frame, said pivoted clamping bar being provided with a finger piece; and spring detent mechanism for maintaining said pivoted clamping bar in operative relationship with said rigid clamping bar and for holding said pivoted bar away from said rigid bar when the clamp is opened by said finger piece.
- 10 36. In a typewriting machine, the combination of a carriage; a platen; a clamping device at one side of said platen; a paper controlling device at the opposite side of said platen, said clamping device comprising a frame movable on said carriage, a clamping bar rigid on said frame, and a co-operative clamping bar pivoted on said frame; and a paper severing blade on said frame above said clamping bars, the paper being advanced over and relatively to said controlling device as it is fed by said clamping device.
- 15 37. In a typewriting machine, the combination of a platen, a pair of co-operating presser bars, means for separating said bars at will to facilitate the introduction of paper, and means for maintaining a spring pressed relationship between said bars, the paper being fed between said bars which remain relatively stationary during the paper feeding operations.
- 20 38. In a typewriting machine, the combination of a platen; paper controlling devices comprising a pair of co-operating presser bars; and means for separating said bars at will to facilitate the introduction of the paper, said means comprising a hand controlled rock shaft and two cam devices on said rock shaft co-operative with the end portions of one of said bars.
- 25 39. In a typewriting machine, the combination of a platen, a pair of co-operating presser bars, means for separating said bars at will to facilitate the introduction of the paper, and a side guide movable across the space between said bars.
- 30 40. In a typewriting machine, the combination of a platen, a pair of co-operating presser bars, means for separating said bars at will to facilitate the introduction of the paper, and a pair of paper side guides mounted on one of said bars.
- 35 41. In a typewriting machine, the combination of a platen; paper controlling devices comprising a pair of co-operating presser bars; means for separating said bars at will to facilitate the introduction of the paper; and a pair of paper side gages arranged near the opposite ends of said bars, said side gages bridging the space between said bars when they are separated.
- 40 42. In a typewriting machine, the combination of a platen, a platen carriage, a presser bar extending lengthwise of the platen and supported on said carriage, a second presser bar provided with pintles at its ends, a pair of swinging arms pivoted on said carriage in which said pintles bear, and spring means co-operative with said second presser bar.
- 45 43. In a typewriting machine, the combination of a platen; a platen carriage; a presser bar extending lengthwise of the platen and supported on said carriage; a second presser bar provided with pintles at its ends, a pair of swinging arms pivoted on said carriage in which said pintles bear, spring means co-operative with said second presser bar; and means for separating said presser bars comprising a rock shaft, cam plates thereon having cam surfaces terminating in dwells, said cam surfaces and dwells co-operating with said pintles, and a hand piece for rocking said rock shaft.
- 50 44. In a typewriting machine, the combination of a carriage; a platen; means for holding a work sheet in a substantially vertical plane opposite the platen, said means comprising two holders, one below and the other above said platen; and devices operating automatically to advance the upper holder step-by-step away from the lower holder to line-feed the paper over the platen.
- 55 45. In a typewriting machine, the combination of a carriage, a platen thereon, a paper carrier mounted on said carriage and adapted to clamp the paper above the platen, a paper guide on said carriage below the platen through which the paper passes, and means for moving said clamp upward step-by-step to advance the paper over the platen.
- 60 46. In a front strike typewriting machine, the combination of an upright carriage, a flat platen thereon, a paper carrier mounted on said carriage and adapted to clamp the paper above the platen, a paper guide on said carriage below the platen through which the paper passes, and means for moving said clamp upward step-by-step to advance the paper over the platen.
- 65 47. In a typewriting machine, the combination of a carriage, a platen thereon, a paper carrier mounted on said carriage and adapted to clamp the paper above the platen, a paper guide on said carriage below the platen through which the paper passes, and means for moving said clamp upward step-

by-step to advance the paper over the platen, said means comprising hand operated rack and pinion devices.

48. In a typewriting machine, the combination of a carriage, a platen thereon, a paper carrier mounted on said carriage and adapted to clamp the paper above the platen, a paper guide on said carriage below the platen through which the paper passes, and means for moving said clamp upward step-by-step to advance the paper over the platen, said means comprising a pair of parallel racks mounted on said clamping carrier, a pair of pinions on said carriage, a shaft on which said pinions are mounted, and hand actuated pawl and ratchet devices for turning said pinions.

49. In a typewriting machine, the combination of a carriage, a platen thereon, a paper carrier mounted on said carriage and adapted to clamp the paper above the platen, a paper guide on said carriage below the platen through which the paper passes, and means for moving said clamping carrier upward step-by-step to advance the paper over the platen, said means comprising a pair of parallel racks mounted on said clamping carrier, a pair of pinions on said carriage, a shaft on which said pinions are mounted, a ratchet wheel on said shaft, a co-operating pawl, and hand devices connected to said pawl and comprising a handle, said handle being also effective to restore the carriage to begin a new line.

50. In a typewriting machine, the combination of a carriage, a platen thereon, a paper carrier mounted on said carriage and adapted to clamp the paper above the platen, a paper guide on said carriage below the platen, means for moving said clamp upward step-by-step comprising pawl and ratchet devices, and releasing means for freeing said clamp from the control of said pawl and ratchet devices.

51. In a typewriting machine, the combination of a carriage, a platen thereon, a paper carrier mounted on said carriage and adapted to clamp the paper above the platen, a paper guide on said carriage below the platen through which the paper passes, and means for moving said clamping carrier upward step-by-step to advance the paper over the platen, said means comprising a pair of parallel racks mounted on said clamping carrier, a pair of pinions meshing with said racks, a shaft on which said pinions are mounted, said shaft having bearings on said carriage, a ratchet wheel on said shaft, a co-operating pawl, a detent normally engaging said ratchet wheel, pawl operating means including a handle, said handle being also effective to restore the carriage, and key actuated devices for rendering said detent inoperative and permitting said clamping carrier to return to normal position.

52. In a typewriting machine, the combination of a carriage; a platen; means for holding a work sheet in a substantially vertical plane opposite said platen, said means comprising a vertically slideable clamp on said carriage; means for moving said clamp upward step-by-step; and releasing means for permitting said clamp to slide back to normal position under the influence of gravity.

53. In a typewriting machine, the combination of an upright carriage, a platen thereon, a vertically slideable paper clamp for feeding the paper over the platen, and line spacing devices for said clamp.

54. In a typewriting machine, the combination of a carriage, a platen thereon, a vertically slideable paper clamp, line spacing devices for said clamp, and means for releasing said clamp so that it may slide downward under the influence of gravity.

55. In a typewriting machine, the combination of a carriage, a platen thereon, a vertically slideable paper clamp, a finger piece effective to open said clamp, and means for releasing said clamp from the control of said line spacing devices so that it may run down under the influence of gravity.

56. In a typewriting machine, the combination of an upright carriage, a platen thereon, a vertically slideable paper clamp for feeding the paper over the platen, a finger piece effective to open said clamp, means for releasing said clamp from the control of said line spacing devices so that it may run down under the influence of gravity, and a paper severing blade.

57. In a typewriting machine, the combination of an upright carriage, a platen thereon, a U-shaped frame slidably mounted on said carriage, releasable paper clamping devices on said frame, and a severing blade on said frame.

58. In a typewriting machine, the combination of an upright carriage, a U-shaped paper clamping frame slidably mounted on said carriage, hand operated means for moving said frame step-by-step, and releasing devices for releasing said frame so that it may slide downward on said carriage under the influence of gravity.

59. In a typewriting machine, the combination of an upright carriage, a U-shaped paper feeding frame slidably mounted on said carriage, hand operated means comprising rack and pinion devices and pawl and ratchet devices for moving said frame upward step-by-step, a spring detent normally co-operative with said ratchet device, and a key actuated arm for throwing said detent out of said ratchet device.

60. In a typewriting machine, the combination of a carriage comprising two frames slidably connected together, step-by-step mechanism for sliding one of said frames

relatively to the other, and material controlling devices on each of said frames, said devices controlling separate sheets.

61. In a typewriting machine, the combination of a carriage comprising two relatively movable frames, step-by-step feeding mechanism for feeding said frames together in one direction, and other step-by-step feeding mechanism for moving one of said frames relatively to the other, said frames controlling separate sheets.

62. In a typewriting machine, the combination of a carriage comprising two relatively movable frames, step-by-step mechanism for affording feeding movements of said frames together in one direction, and other step-by-step feeding mechanism for moving one of said frames relatively to the other for line spacing in a direction at right angles to the direction of the first step-by-step movement, said frames controlling separate sheets.

63. In a typewriting machine, the combination of a carriage, letter feeding devices therefor, two bodily movable carriers on said carriage, means for advancing said carriers independently of each other on said carriage, and key actuated tabulating mechanism effective to release said carriage from said letter feeding devices and to arrest it at predetermined points.

64. In a typewriting machine, the combination of an upright carriage frame, a platen arranged transversely of said carriage frame, vertically slideable paper feeding devices on said carriage frame, letter feeding devices for said carriage frame, and a key actuated tabulating mechanism comprising a column stop bar fixed to the lower part of said carriage frame and extending transversely thereof, said tabulating mechanism being effective to release said carriage from its letter feeding devices and to arrest it at predetermined points.

65. In a typewriting machine, the combination of a carriage, letter feeding devices therefor, two bodily movable carriers on said carriage, and means for advancing said carriers independently of each other on said carriage, said means comprising a worm gearing for one of said carriers.

66. In a typewriting machine, the combination of a carriage, letter feeding devices therefor, a platen on said carriage, a controller on said carriage, and a worm feed for moving said controller gradually on said carriage transversely of the direction of letter feeding movement.

67. In a typewriting machine, the combination of a carriage, letter feeding devices therefor, a platen on said carriage, a controller on said carriage, a worm feed for moving said controller gradually on said carriage transversely of the direction of letter feeding movement, and devices for en-

abling said controller to be moved backward continuously by hand while said worm feed remains in connected relationship.

68. In a typewriting machine, the combination of a carriage, letter feeding devices therefor, a platen on said carriage, a controller on said carriage, and automatically operating worm feeding devices for moving said controller gradually on said carriage transversely of the direction of letter feeding movement.

69. In a typewriting machine, the combination of a carriage, letter feeding devices therefor, a platen on said carriage, a controller on said carriage, and a worm feed for moving said controller gradually on said carriage transversely of the direction of letter feeding movement, said worm feed being operative automatically when carriage is returned to begin a new line.

70. In a typewriting machine, the combination of a carriage, letter feeding devices therefor, a platen on said carriage, a controller on said carriage, means for moving said controller bodily step-by-step on said carriage transversely of the letter feeding movement thereof, a second controller on said carriage independent of said first recited controller, and devices comprising worm gearing for slowly advancing said second controller.

71. In a typewriting machine, the combination of a carriage, letter feeding devices therefor, a platen on said carriage, a controller on said carriage, means for moving said controller bodily step-by-step on said carriage transversely of the path of letter feeding movement thereof, a second controller on said carriage independent of said first recited controller, and a worm feed for said second controller, said worm feed being automatically operative when the carriage is returned to begin a new line of writing.

72. In a typewriting machine, the combination of a carriage; letter feeding devices therefor; a platen on said carriage; a controller on said carriage; means for moving said controller bodily step-by-step on said carriage transversely of the letter feeding movement thereof, said means comprising a line spacing handle effective to return the carriage at the end of the line of writing; a second controller on said carriage; a worm feed for said second controller; and stop devices effective to arrest the carriage during its return movement, certain of said stop devices automatically actuating said worm feed.

73. In a typewriting machine, the combination of a traveling carriage, devices for feeding paper mounted on said carriage, a bodily movable carbon carrier on said carriage, and means for advancing said carbon carrier relatively to the paper.

74. In a typewriting machine, the combi-

nation of a traveling carriage, letter feeding devices for said carriage, devices for feeding paper mounted on said carriage, a carbon carrier on said carriage, a detachable carbon holder on said carrier, and means for advancing said carrier together with the holder relatively to the paper.

75. In a typewriting machine, the combination of a traveling carriage, letter feeding devices for said carriage, devices for feeding a plurality of printing surfaces mounted on said carriage, a carbon carrier on said carriage, a plurality of detachable carbon holders on said carriage interleaved with said printing surfaces, and means for moving said carbon carrier and said holders in a direction to advance the carbon paper carried by said holders relatively to the printing surfaces.

76. In a typewriting machine, the combination of a traveling paper carriage, line spacing means for the paper on said carriage, a carbon carrier movably mounted on said carriage, and means independent of the line spacing means for spacing the carbon carrier to feed the carbon paper.

77. In a typewriting machine, the combination of a traveling carriage, letter feeding devices for said carriage, devices for feeding paper mounted on said carriage, a carbon carrier on said carriage, and a worm feed for said carbon carrier.

78. In a typewriting machine, the combination of a traveling carriage, letter feeding devices for said carriage, devices for feeding paper mounted on said carriage, a carbon carrier on said carriage, and a worm feed for said carbon carrier, said worm feed being automatically operative when the carriage is returned at the end of a line.

79. In a typewriting machine, the combination of a traveling carriage, a carbon carrier mounted to slide vertically on said carriage, a plurality of carbon holders attached to said carrier, said holders being adapted to be detached from said carrier by a movement in a direction at right angles to the sliding movement of said carrier, and means for normally holding said carrier from sliding and for preventing said holders from dropping under the force of gravity.

80. In a typewriting machine, the combination of a traveling carriage, letter spacing devices therefor, paper feeding devices, carbon holders each provided with a sheet of carbon paper, and sets of devices arranged at opposite sides of the carriage on which said carbon holders may be mounted in alternation, each set of devices being common to all of the carbon holders supported at its side of the machine.

81. In a typewriting machine, the combination of a traveling carriage, letter spacing devices therefor, paper feeding devices, carbon holders each provided with a sheet of carbon paper, sets of devices arranged at op-

posite sides of the carriage on which said carbon holders may be mounted in alternation, each set of devices being common to all of the carbon holders supported at its side of the machine, and means for simultaneously actuating said sets of devices to advance the carbon holders and the sheets carried thereby.

82. In a typewriting machine, the combination of a traveling carriage, letter spacing devices therefor, paper feeding devices, carbon holders each provided with a sheet of carbon paper, and sets of pins at opposite sides of the carriage with which said carbon holders may be detachably engaged in alternation, each set of pins providing a common support for all of the carbon holders mounted at its side of the machine.

83. In a typewriting machine, the combination of a vertical traveling carriage frame, a vertical carbon carrier slidable up and down on said frame, a plurality of carbon paper holders on said carrier, said holders with their carbon sheets being detachable from the back thereof by horizontal movements, and a vertically movable paper controller for advancing a plurality of printing surfaces independently of the carbon sheets with which said printing surfaces are interleaved.

84. In a typewriting machine, the combination of a traveling carriage, a slide frame movable up and down on said carriage, pairs of pins projecting horizontally rearward from said slide frame at opposite sides thereof, and a plurality of carbon holders detachably engaging with each pair of pins, each of said carbon holders carrying a separate sheet.

85. In a typewriting machine, the combination of a traveling carriage frame, a carbon carrier slidable up and down on said frame, pairs of pins projecting from said carrier, and a plurality of carbon holders cooperating with each pair of pins, the carbon holders being connected with opposite sets of pins in alternation, each of said carbon holders carrying a separate sheet.

86. In a typewriting machine, the combination of a traveling carriage frame, a carbon carrying frame movably mounted on said carriage frame and provided with sets of pins, and a plurality of angular frames each provided with holes adapted to fit over one of said sets of pins, each of said angular frames being provided with a separate strip of carbon paper.

87. In a typewriting machine, the combination of a traveling paper carriage, a carbon carrier frame movably supported thereon, means for detachably mounting separate carbon strips on said frame, and means for advancing said movable frame to advance or feed the carbon strips relatively to the paper carried by said carriage.

88. In a typewriting machine, the combi-

- nation of a traveling paper carriage, a carbon carrier frame movably supported thereon, sets of pins projecting from said carrier frame, each set being adapted to carry a plurality of detachable strips of carbon paper, and means for advancing said carrier frame relatively to said carriage to advance the strips of carbon paper relatively to the paper carried by said carriage.
- 10 89. In a typewriting machine, the combination of a traveling carriage frame, a carbon carrying frame provided with parallel racks, a shaft on said carriage frame having pinions co-operative with said racks, and means for actuating said shaft during traveling movements of said carriage.
- 15 90. In a typewriting machine, the combination of a traveling carriage frame, a carbon carrying frame provided with parallel racks, a shaft on said carriage frame having pinions co-operative with said racks, and means for actuating said shaft during traveling movements of said carriage, said shaft also being provided with a finger piece by 25 which it may be operated to move the carbon carrier at will.
- 20 91. In a typewriting machine, the combination of a traveling carriage frame, a carbon carrying frame provided with parallel racks, a shaft on said carriage frame having pinions co-operative with said racks, and means for actuating said shaft comprising a worm feed by which a creeping movement 30 may be communicated to the carbon paper carried by said carbon carrying frame.
- 25 92. In a typewriting machine, the combination of a traveling carriage frame, a carbon carrying frame provided with parallel racks, a shaft on said carriage frame having pinions co-operative with said racks, and means for actuating said shaft, said means comprising a pinion near one end of said shaft, a worm with which said pinion meshes, and means for turning said worm automatically.
- 30 93. In a typewriting machine, the combination of a traveling carriage frame, a carbon carrying frame provided with parallel racks, a shaft on said carriage frame having pinions co-operative with said racks, and means for actuating said shaft during traveling movements of said carriage, said means comprising a pinion near one end of said shaft, a worm with which said pinion meshes, a ratchet wheel rigid with said worm, a 35 spring pressed pawl engaging said ratchet wheel, a slidably mounted pawl carrier, and a relatively stationary stop with which said pawl carrier co-operates.
- 35 94. In a typewriting machine, the combination of a traveling carriage frame, a carbon carrying frame movably mounted thereon, and means for progressively moving said carbon carrying frame to communicate a creeping feed to the carbon paper carried thereby.
- 40 95. In a typewriting machine, the combination of a traveling carriage frame, a carbon carrying frame thereon, means for progressively moving said carbon carrying frame to feed the carbon paper carried thereby, and devices for varying the extents of progressive movements of said carbon carrying frame.
- 45 96. In a typewriting machine, the combination of a traveling carriage frame, a carbon carrying frame thereon; means for progressively moving said carbon carrying frame to feed the carbon paper carried thereby comprising worm gearing, a ratchet wheel, 50 a co-operating pawl and a slidable spring pressed pawl carrier, and devices for varying the extents of progressive movements of said carbon carrying frame, said devices comprising an adjustable screw stop on said pawl carrier that normally contacts with a relatively stationary part.
- 50 97. In a typewriting machine, the combination of an upright traveling carriage, a carbon carrying frame vertically slidable 55 thereon, a pair of racks on said carbon carrying frame, a horizontal shaft on said carriage, pinions on said shaft meshing with said racks, a pinion frictionally mounted on said shaft near one end, an upright worm shaft on said carriage, a worm on said upright shaft meshing with said last named pinion, and means for automatically turning said worm.
- 55 98. In a typewriting machine, the combination of an upright traveling carriage, a carbon carrying frame vertically slidable 60 thereon, a pair of racks on said carbon carrying frame, a horizontal shaft on said carriage, pinions on said shaft meshing with said racks, a pinion frictionally mounted on said shaft near one end, an upright worm shaft on said carriage, a worm on said upright shaft meshing with said last named pinion, means for turning said worm shaft 65 automatically during traveling movements of the carriage, and a finger piece on said horizontal shaft for turning it at will without affecting said worm.
- 60 99. In a typewriting machine, the combination of a traveling carriage frame, a carbon carrying frame movably mounted thereon, and means for progressively moving said carbon carrying frame to communicate a creeping feed to the carbon paper carried 70 thereby, said means comprising a worm and pinion operative by pawl and ratchet devices.
- 65 100. In a typewriting machine, the combination of a traveling carriage frame, a carbon carrying frame movably mounted thereon, and means for progressively moving said carbon carrying frame to communicate a creeping feed to the carbon paper carried 75

- thereby; said means comprising a worm and pinion and devices for actuating said worm comprising a ratchet wheel, a co-operating pawl and a pawl carrier.
- 5 101. In a typewriting machine, the combination of a traveling carriage frame; a carbon carrying frame movably mounted thereon; means for progressively moving said carbon carrying frame to communicate a creeping feed to the carbon paper carried thereby, said means comprising a worm and wheel and devices for actuating said worm comprising a ratchet wheel, a co-operating
- 10 pawl, and a pawl carrier; and an adjustable stop on said pawl carrier for varying the 15 throw of said pawl and the consequent extent of turning movement communicated thereby to said ratchet wheel.
- Signed at Arlington, in the county of Hudson and State of New Jersey, this 28th 20 day of August, A. D. 1919.
